ABSTRACT: A tamper-proof container closure for use on containers such as pharmaceutical bottles or the like to hold a stopper in place in the opening of the bottle. The container closure comprises a cap and cover member. The cap is generally of cuplike form and includes a top and a skirt depending from the outer peripheral edge of the top. The top includes a portion connected to the cover member and adapted to be detached to expose the stopper and permit it to be pierced, for example by a hypodermic syringe to remove the fluid contents of the container. In one form of the invention, partial scoring, that is, a continuous line-type scoring, is provided in the top to define a keyhole-shaped detachable portion therein. The cover member is secured to this detachable keyhole-shaped portion whereby upon actuation of the cover relative to the cap, the detachable portion breaks away from the remainder of the cap along the score line.

CONTAINER CLOSURE HAVING INTEGRAL OPENING MEANS

This invention relates to improvements in container closures and in particular to caps for pharmaceutical containers or bottles having a removable portion adapted to be detached to permit piercing of the stopper by a syringe for removing the contents of the container.

An example of a container closure of this type is shown in U.S. Pat. No. 3,071,274, owned by the assignee of the present application. As illustrated therein, these container closure assemblies usually include a pierceable closure member such as a disk or stopper formed of rubber or like material which disk in the open end of the bottle and a metallic cap to hold the stopper in place, the cap having a depending flange engaging a shoulder on the neck of the bottle to hold the stopper in place. These caps generally include a central removable disk portion connected to the annular top portion of the cap usually by a plurality of circumferentially spaced fracturable connecting bridges. The assembly further includes a cover member overlying the top and connected to the central disk whereby upon pivotal movement of the cover member, the fracturable bridges are broken and the disk is removed to expose the stopper and afford access thereto which then may be pierced by a hypodermic syringe to remove the contents of the container or bottle.

While this container closure assembly is generally effective for the purposes intended, there are some problems encountered in the manufacture and use thereof. For example, these container closures are designed to be removed by a one-hand operation wherein the container is supported in the hand and the thumb is used to pry the cover upwardly. In some instances, it has been found that it is difficult to mass produce the caps so that the fracturing point of the bridges is substantially uniform. This is important for the reason that if the bridges offer too much resistance it is difficult for the user to remove it in a one-hand operation. On the other hand if the bridges fracture too readily, there is the danger of premature breakage during manufacturing and handling processes. Furthermore, if the fracturing strength of the bridges is predictable and uniform the resistance to removal of the cover may vary depending on where the peripheral edge of the cover is engaged by the user.

In accordance with the present invention, the central removable disk portion is connected to the annular top portion of the cap by means of a partial score line, the partial scoring defining in one embodiment a tab portion converging to a point along the skirt of the cap. The disk is provided with an opening offset from the center thereof and aligned with a line through the center of the cap portion and the cover has a button engaging through the opening to secure the cover to the assembly. Further, the cover is provided with a recess adjacent the edge providing a lift section for engaging the cover to remove the central disc disk portion. By this arrangement, the force required to remove the cover member and disk may be controlled more accurately and made more uniform. Furthermore, this assembly is much more economical to make.

These and other objects and the various features and details of the construction and arrangement of a container closure in accordance with the present invention are hereinafter more fully set forth with reference to the accompanying drawing, wherein:

FIG. 1 is a side elevational view of a container closure in accordance with the present invention in position on a bottle;

FIG. 2 is an enlarged plan view of the cap with a portion of the cover element broken away to more clearly illustrate the construction;

FIG. 3 is a sectional view taken on lines 3—3 of FIG. 2;

FIG. 4 is a view similar to FIG. 3 with cover member and disk partially removed;

FIG. 5 is a perspective view of the cap and cover member and disk disassembled from the remainder of the cap;

FIG. 6 is a perspective view of the cap prior to assembly of the cover member thereto;

FIG. 7 is a transverse sectional view of a second embodiment of container closure in accordance with the present invention assembled to a container;

FIG. 8 is a perspective view of the cap portion of the container closure;

FIG. 9 is a transverse cross-sectional view of a third embodiment of container closure in accordance with the present invention;

FIG. 10 is a perspective view of the cap;

FIG. 11 is also a perspective view showing the interior of the cap;

FIG. 12 is a perspective view showing the container closure after removal from the container;

FIG. 13 is a side elevational view of a fourth embodiment of container closure applied to a conventional bottle;

FIG. 14 is a view similar to FIG. 13 as viewed from the opposite side of the container closure;

FIG. 15 is a top plan view with parts broken away to show more clearly the construction of the container closure shown in FIGS. 13 and 14;

FIG. 16 is a sectional view taken on line 16—16 of FIG. 15;

FIG. 17 is a view similar to FIG. 16 showing the container closure partially removed; and

FIG. 18 is a perspective view of the cover member after disassembly from the remainder of the container closure.

Referring now to the drawings and particularly to 1—3 thereof, reference numeral 10 designates generally a container such as a bottle of conventional form, having a container closure in accordance with the present invention covering the opening in the bottle. This bottle includes a reduced neck portion 12 having a peripherally extending rib 14 adjacent the opening 16 in the bottle. As seen in FIGS. 3 and 4, a stopper 18 which may be formed of rubber or like material engages in the opening 16, the stopper in the present instance has a depending plug portion 20 adapted to fit within the neck of the bottle, a peripheral flange 22 which seats against the lip of the bottle and a central thin walled portion 24 which may be pierced for example by the needle of a hypodermic syringe to withdraw the contents of the container. The stopper 18 may be of any conventional form and the present invention is not concerned with the particular form thereof.

A cap 30 of generally cup like form which is preferably made of a sheet material such as aluminum holds the stopper in place and also serves to seal the contents of the container. The cap 30 includes a depending peripheral skirt 32 adapted to be spun inwardly or otherwise formed along its lower terminal edge to provide an inwardly directed locking flange 34 engaging under the rib 14 to secure the stopper in place.

In accordance with the present invention, the top 36 of the cap is provided with a partial scoring broadly designated by the numeral 40 which as best illustrated in FIG. 2 comprises a circular portion 42 separating the top into an outer annular portion 44 and a circular disk portion 46, the circular scoring 42 terminating in a pair of spaced-apart parallel score lines 48 extending across the annular portion 44 and defining there between a tab portion 50. The score lines 48 are parallel and disposed on opposite sides of a line through the center of the top and as illustrated in FIGS. 5 and 6 converge to a point in the sidewall of the cap to define a generally triangular tail extension 52 of the tab portion 50. An opening 60 is provided in the central disk portion 46 offset to one side of the center of the disc diametrically opposed from the tab portion 50 and as illustrated has an embossed or raised wall portion 62 defining a recess or pocket on the underside of the top.

A cover member 70 is connected the top of the cap with is actuatable with respect thereto to remove the central disk portion and tab portion from the remainder of the cap. To this end the cover which is of generally disklike form overlies the top of the cap and is secured to the removable disc portion by a buttonlike projection 74 which engages through the opening 60. This button has an out-turned locking flange 76 engaging about the inner peripheral wall of the embossed wall 62 surrounding the opening 60. As illustrated the cover member has a peripherally sidewall or flange 80 which overlies and snugly

the circumferential edge of the cap at the juncture of the top and skirt. The cover member has a cutout 82 in the side wall located at a point in line with the opening 60, center of the cap and tab portion 50. This cutout 82 is to facilitate actuation of the cover member to remove the central disk portion from the cap and expose the stopper so that it may be pierced by a hypodermic syringe. By this construction, the user simply inserts a prying instrument or the fingernail in the cutout and while supporting the container in the opposite hand, exerts a lifting force on the cover which effects separation along the partial score lines, and complete removal of the central disk and tab portion from the remainder of the cap.

The entire assembly is economical to make. For example, the cap may be made of a flat disklike piece of aluminum and then by conventional means is partially scored to form the score lines 42, 48 and 51 and simultaneously or in a separate operation the opening 60 and embossed wall 62 formed. After the disk is shaped to the form of a cap with a straight-sided skirt, a cover member which may be made of plastic is assembled thereto. It is noted that the cover may be secured to the cap in the manner shown by peening of the button 74 after assembly of the cover and cap as by applied pressure and heat.

It is noted that the term "partial scoring" as used herein is a continuous score line in the metallic member which may be made by conventional means. Further, the depth of penetration of the score line is selectively chosen for a particular gauge metal to provide the desired resistance to removal of the disk member.

There is shown in FIGS. 7 and 8 another embodiment of container closure in accordance with the present invention. This container closure which is generally designated by the numeral 100 is adapted to be assembled over the open end of a container such as a bottle 110 identical in form to the container of the previously described embodiment including a reduced neck 112 and a circumferentially extending rib 114 surrounding the opening. The cap holds a conventional stopper 118 in the opening 116 in the neck of the bottle. As illustrated, the container closure includes a cap 122 having a generally cylindrical skirt portion 124 and a top 126. In the present instance, however, the top is provided with a circular partial score 128 separating the top into an outer annular portion 130 and a central disk portion 132. Further the central disk portion has an opening 136 surrounded by an embossed or raised wall portion 138 disposed centrally of the cap. In this embodiment of the invention the cover member 140 which may be made of a plastic material has a central depending projection 142 in the form disk a button having a peripheral flange engaging in the pocket defined under the raised wall 138 surrounding the opening 136. The cover member has an outer downwardly depending sidewall snugly embracing the juncture of the skirt and top portions of the cap.

In accordance with this embodiment, the cover may be engaged at any point about its periphery and when it is actuated relative to the top, the partial score is fractured along the circular line 128 and the entire central disk portion is removed with the cover to expose the center or pierceable portion of the stopper 120. The cap may be made and the cover assembled thereto in the manner described above in connection with the first embodiment.

There is illustrated in FIGS. 9-12 inclusive a third embodiment of container closure in accordance with the present invention. This form which is generally designated by the numeral 200 is adapted to be applied to a container to hold a stopper over the opening in a container such as the bottle 202. This bottle is of the same construction as in the previous described embodiments and includes a reduced neck 204, a peripherally extending radially outwardly projecting rib 206 adjacent the opening 208 in the upper end of the bottle.

The container closure 200 includes a cap 210 of generally cuplike form having a top 212 and a skirt 214 depending from the outer peripheral edge of the top which is adapted to be crimped or spun inwardly adjacent its lower end to engage under the rib 206 to hold the stopper 220 in place over the

open end of the container. As illustrated, the stopper 220 is a flat disklike member made of a resilient material such as rubber. In the present instance the cap is designed to be completely removed from the container and to this end is provided with partial scoring in a configuration as illustrated in FIGS. 10 and 11. More specifically, a partial score line 222 is provided in the top 212 of generally keyhole configuration to divide the top into an outer horseshoe-shaped annular portion 226 and a central removal portion 228. The parallel legs 228a and 228b of the partial scoring in the top extend over the side edge and in the sidewall converge inwardly as illustrated as at 230a and 230b. Leg 230b terminates at a point short of the lower terminal edge of the skirt whereas the leg 230a has a lower extension 232 spaced from the upper extension for a purpose to be described in more detail hereafter. The area of the cap between the score lines 228a, 228b and 230a, 230b defines a tab portion 240. The cap is also partially scored diametrically opposed from the tab portion 240, consisting of a single score 244 extending across the top and down the skirt and a short leg portion 246 spaced from the line 244 and extending to the lower edge of the skirt.

The central portion 228 is provided with an opening 250 at a point offset from the center of the cap toward the score line 244, the opening 250 being surrounded by a raised wall portion 252.

The container closure further includes a cover member 260 of generally disklike form and made of a resilient material such as plastic. The cover member has a depending projection 262 engaging through the opening 250 in the top of the cap which is of buttonlike form and has an outwardly extending flange 264 engaging under the wall 252 and in the pocket formed by the raised wall portion. The cover member has an indenture or cutout 266 aligned with the projection 262 and center of the cover member to facilitate insertion of a fingernail or other prying instrument to actuate the cover member at this point relative to the cap. When an upward force is applied in the area of the cutout 266, the cap is fractured along the keyhole score line 222 to remove the center portion 228. With this portion of the cap raised, the user continues to pull the cover member radially outwardly and downwardly along the skirt to fracture the cap along the lines 228a, 228b and 230a, 230b. Because of configuration of the score lines 230a and 230b, the skirt will separate completely along the score lines 230a, 232, to permit the remainder of the cap to be pivoted about the score lines 244 and 246, the area between these lines serving as a hinge as at 270 whereby the remainder of the cap may be divided in halves and completely removed from the container (See Fig. 12).

The cap and its scoring configuration may be formed from a flat circular disklike piece of aluminum or the like and then made into a cuplike form by conventional means. Thereafter, the cover member may be assembled to the cap in the manner described in connection with the previous embodiments.

There is shown in FIGS. 13-18 inclusive a fourth embodiment of container closure in accordance with the present invention. The container closure is generally designated by the numeral 300 and as in the previously described embodiments, is adapted to be assembled over the open end of a container such as the bottle 310, the bottle including a reduced neck 312 and a circumferentially extending rib 314 surrounding the opening in the container. The container closure supports a conventional stopper 318 in the opening 316 in the neck of the container, the stopper having in the present instance a central depending portion which has a center section of thinner cross section so that it may be pierced by a hypodermic syringe.

The container closure includes a cap 301 of generally cuplike form which is preferably made of a sheet material such as aluminum and which serves to hold the stopper in place thereby sealing the contents of the container. The cap 301 includes a depending peripheral skirt 320 adapted to be spun inwardly or otherwise formed along its lower terminal edge to provide an inwardly directed locking flange 334 engaging under the rib 314 of the container.

The top 336 of the cap is provided with a continuous partial score line broadly designated by the numeral 340, which as best illustrated in FIGS. 14 and 15, is of keyhole configuration in the top and converges to a pointed tail portion 341 in the sidewall of the skirt. It is noted that the continuous score line is referred to herein as "partial scoring" and is of a sufficient depth in relation to the thickness of the sheet material to permit separation of the cap along the score line by a predetermined force as explained in more detail hereafter. Depth of the partial scoring can be controlled for any gauge metal thereby providing an assembly wherein the force to remove the disk portion of the cap may be accurately controlled. More specifically, the scoring 340 separates the cap into an outer annular horseshoe shaped portion 344, a central disk portion 346 and a tab portion 347 between parallel radial score lines 348 extending across the annular portion. The extension of score lines 348 as illustrated in FIG. 14 converge to a point in the skirt of the cap to define a generally triangular tail extension 352 of the tab portion 347.

In the present instance the central disk portion 346 has an opening 360 therein of square cross section which is offset to one side of the center of the disk diametrically opposed from the tab portion 347. The disk has an embossed or raised wall portion 362 surrounding the opening defining a recess or pocket on the underside of the top.

A cover member 370 which may be made of plastic is connected to the top of the cap and is actuatable with respect thereto to remove the central disk portion and tab portion from the remainder of the cap. To this end the cover 370, which is generally of disklike form overlies the top of the cap and is secured to the removable disk portion by a button like projection 374 gauging through the opening 360. The projection has a square throat portion 375 conforming to the opening 360 and an out-turned locking flange 376 which nests in the pocket defined by the raised wall portion of the disk. By this construction the cover member is retained against rotational movement relative to the cap for a purpose described hereinafter. The cover member has a peripherally extending sidewall 380 which overlies and snugly embraces the circumferential edge of the cap at the junction of the pocket and skirt. The cover member also has a pair of diametrically opposed lugs 381 and 383, the lug 383 serving as a means for engagement by the finger of the user to actuate the cover member relative to the cap to thereby remove the central disk portion. The lug 381 as illustrated in FIG. 14 extends down the skirt of the cap to a point slightly below the apex of the triangular tail extension of the cap and serves as a lever point upon actuation of the cover as shown in FIG. 17 to provide easy removal of the cover and disk portion when desired by the user.

When it is desired to expose the stopper for penetration by a hypodermic syringe to remove the contents, the user simply supports the container in one hand and now engages the lug 383 and presses it upwardly whereby the cover member lifts the central disk portion and causes it to be separated from the remainder of the cap along the score lines 340. Note in FIG. 17 that the lug 381 presses against the skirt of the cap below the apex of the triangular extension to insure complete separation and exertion of a minimum force to remove the disk portion.

The cap and cover assembly is economical to make and can be made in much the same manner as previously described embodiments. Thus, the cap may be made of a flat, disklike piece of aluminum and then by conventional means "partially scored" to form the continuous score line 340 defining the central disk portion 346, the tab portion 347 and the tail extension 352. After the disk is shaped to the form of the cap, the cover member is secured thereto simply by peening the button by applied pressure and heat. Further, it is noted that the depth of the continuous "partial scoring" can be controlled for any gauge metal thereby providing an assembly where the force for removing the disk portion may be controlled very accurately and very uniformly for a plurality of container closures.

The container closure of the present invention provides a truly tamper-proof construction for the reason that once the cover member and portion of the case have been removed to expose the stopper, they cannot be replaced or reassembled. Furthermore, removal of the cover member does not produce any jagged edges on the cap which might present a risk of injury to the user. Additionally, the cover member closely embraces the cap to provide a seal that excludes infiltration of dirt and foreign matter, thus eliminating the danger of contaminating the contents of the container.

While particular embodiments of the invention have been illustrated and described herein, it is not intended to limit the invention and changes and modifications may be made therein within the scope of the following claims.

We claim:

1. In a tamper-proof closure for closing an opening in a container or the like, a cap which is adapted to be secured to the container over the opening and including a top, means defining a partial score line in said cap providing an area of reduced cross section and defining a detachable portion adapted to be detached, a cover member overlying the top secured to said detachable cap portion and having an outer edge portion extending beyond the periphery of the top engageable by the user to actuate the cover member relative to the cap to effect separation along said partial score line.

2. A tamper-proof closure as claimed in claim 1 wherein the partial scoring is in the form of a circular score line in the top dividing the top into an outer annular portion and a circular central disk portion, the circular score line terminating in a pair of spaced-apart score lines extending across the annular portion and defining therebetween a tab.

3. A tamper-proof closure as claimed in claim 2 wherein the parallel score lines converge to a point in the sidewall in the cap defining a triangular tail extension of the tab.

4. A tamper-proof closure as claimed in claim 1 wherein said cover member is generally disk-shaped and has an outer wall overlying the juncture of the top and skirt of the cap.

5. A tamper-proof closure as claimed in claim 4 wherein said cover member is made of plastic.

6. A tamper-proof closure as claimed in claim 1 including means defining an opening in the detachable portion of the cap and wherein said cover member has a depending projection engaging through said opening terminating in a flange underlying the wall surrounding said opening.

7. A tamper-proof closure as claimed in claim 6 wherein said opening is offset relative to the center of the cap and wherein said cover member is provided with a recess in one peripheral edge aligned with said opening and the center of the cap.

8. A tamper-proof closure as claimed in claim 1 wherein said partial scoring is in the form of a complete circle to define a central removable disk portion.

9. A tamper-proof closure as claimed in claim 8 including an opening in the center of said disk portion and wherein said cover member is provided with a depending projection engaging through said opening terminating in a flange underlying the wall surrounding said opening.

10. A tamper-proof closure as claimed in claim 1 wherein said scoring is of a configuration so that the top may be completely removed from the container. c

11. A tamper-proof closure as claimed in claim 1 wherein said detachable portion includes a tail section in the skirt and wherein said cover member includes at least one lug overlying the tail section, the lower extremity of said lug extending beyond said tail section to provide a pivot upon actuation of said cover member relative to the cap.

12. In a tamper-proof closure adapted to hold a stopper in place in the opening of a container or the like, a cap including a top and a skirt depending from the outer peripheral edge of the top having means for securing the cap to the container, means defining a continuous partial score line in said cap providing an area of reduced cross section and defining a detachable portion adapted to be detached, a cover member

overlying the top secured to said detachable portion and having an outer edge portion extending beyond the periphery of the top engageable by the user to actuate the cover member relative to the cap to effect separation of the cap along the partial score line.

13. In a tamper-proof closure for closing an opening in a container or the like, a cap adapted to be secured to the container over the opening and including a top, means defining a partial score line in said cap providing an area of reduced cross section and defining a detachable portion adapted to be detached, a cover member overlying the top secured to said detachable portion, said cover member having an outer edge portion extending beyond the periphery of the top and a pivot portion remote from the outer edge portion and extending to a point beyond the score line defining the detachable portion, said outer edge portion engageable by the user to actuate the cover member relative to the cap to effect separation of the cap along the partial score line, said pivot portion serving as a

fulcrum of a lever upon actuation of the cover member.

14. In a tamper-proof closure adapted to hold a stopper place in the opening of a pharmaceutical bottle or the like, a cap including a top and a skirt depending from the outer peripheral edge of the top, means defining a partial score line in said cap providing a detachable portion adapted to be detached, a cover member overlying the top and secured to said detachable portion of the cap, actuation of said cover member relative to the cap adapted to effect separation of the cap along said partial score line, said means for securing the cover to the cap including means defining a noncircular opening in the detachable portion of the cap and a depending projection on said cover engaging through said opening of a cross section similar to said noncircular opening to prevent relative rotation of said cover and cap, said projection terminating in a flange underlying the wall surrounding said opening.
